UNITED STATES PATENT OFFICE.

ROBERT WEEKS, OF HAMILTON, ONTARIO, CANADA.

DESIGN FOR AN ANTISKID AUTOMOBILE-TIRE CHAIN.

51,468.

Specification for Design.

Patented Nov. 6, 1917.

Application filed July 30, 1917. Serial No. 183,599. Term of patent 14 years.

To all whom it may concern:

Be it known that I, ROBERT WEEKS, a citizen of the United States, residing at Hamilton, in the county of Wentworth, Province of Ontario, Dominion of Canada, have invented a new, original, and ornamental Design for an Antiskid Automobile-Tire Chain, of which the following is a speci-

fication, reference being had to the accompanying drawing, forming part thereof.

The figure is a plan view of a section of the tire chain showing my new design.

I claim:

The ornamental design for an antiskid automobile tire chain, as shown.

ROBERT WEEKS.
